CURTAIN AND SHADE SUPPORT

Robert E. Ratcliffe, Dallas, Tex.

Application October 5, 1939, Serial No. 298,136

5 Claims. (Cl. 248—254)

This invention relates to a curtain and shade support and it is one object of the invention to provide a device of this character adapted to be mounted across the upper portion of a window frame and serve as supporting means for a wood curtain pole, a metal curtain rod, or a shade roller.

Another object of the invention is to provide a device of this character which may support a main curtain and also overdrapes in such a manner that the overdrapes will be supported in proper relation to the main curtain.

Another object of the invention is to so form the bracket that when a pair of brackets are mounted at opposite sides of the window frame a shade roller may be mounted over the inner or lower sash in such a position that it will not be in the way and interfere with the lace curtains or detract from the appearance thereof.

Another object of the invention is to provide a bracket formed of metal strips appropriately bent to form elements of the bracket which are riveted or otherwise firmly secured to each other.

Another object of the invention is to provide a bracket which is of simple construction, very strong and of light weight.

The invention is illustrated in the accompanying drawings, wherein:

Fig. 1 is a perspective view of a window having brackets of the improved construction mounted at opposite sides of its upper portion.

Fig. 2 is a view showing the window frame in transverse section and the brackets and a curtain rod carried thereby in bottom plan, the view being taken on the line 2—2 of Fig. 3.

Fig. 3 is a view taken on the line 3—3 of Fig. 2.

Fig. 4 is a perspective view of a bracket element for supporting a wooden curtain pole.

Fig. 5 is a perspective view of a bracket element for holding a metal curtain rod.

Fig. 6 is a similar view of a modified form of bracket.

Fig. 7 is a perspective view of the upstanding rod engaging element shown in Fig. 6.

The improved curtain support or bracket is for use on a window frame 1, a pair thereof being used and located at opposite sides of the upper portion of the window frame, as shown in Fig. 1. Each support consists of a main bracket 2 and an auxiliary bracket 3 carried by and extending upwardly from the main bracket. The bracket 2 constitutes a mounting for a rod carrying a main curtain and the auxiliary bracket serves to support a rod for overdrapes or as a support for a curtain pole from which a lace curtain may be hung if no overdrapes are used.

Referring to Figs. 2 and 6, it will be seen that the main bracket is formed from a strip of metal bent intermediate its length to provide a shank 4 and an arm 5 extending laterally therefrom in

an outward direction for causing it to extend horizontally across the adjacent side portion 6 of the window frame. In spaced relation to its end, the shank is bent laterally, as shown at 7, to provide an offset portion 8 for fitting into the upper end of the adjacent track 9 for the inner sash of the window. The two brackets are firmly secured in the tracks 9 by screws or equivalent fasteners 10 passed through openings 11 formed in the offset portions of their shanks and into the window frame, as shown in Fig. 2.

A bracket 12 may be mounted in depending relation to each shank, as shown in Fig. 3, or each shank may be formed with a socket 13 to receive the pintle or key of a shade roller. It will be understood that the bracket 12 or socket 13 receiving the winding key of the shade roller will be of proper shape and dimensions to receive the same, whereas the pintle will be received in a circular socket to permit turning of the roller. After the strip has been bent to form the shank 4 and the arm 5, the arm forming portion is folded outwardly back upon itself to form a tongue 14 extending in spaced and substantially horizontal relation to the arm. The tongue is of such length that its free end terminates substantially even with the inner end of the arm. The tongues of the two brackets are disposed in alignment with each other when the brackets are secured to the window frame and their free ends are adapted to fit into ends of a hollow curtain rod 15 and support the rod across the window frame in position to carry a curtain. The curtain rod may consist of a single flat tube or channelled strip, as shown in Figs. 2 and 3, or it may consist of companion sections in telescoping engagement with each other so that they may be longitudinally adjusted to fit the window frame.

The auxiliary bracket is also formed from a metal strip. The auxiliary bracket is disposed vertically so that it extends upwardly from the main bracket and the lower portion of the strip is bent to form a U-shaped base or foot 16 at the lower end of the shank 17 of the bracket. This foot fits between the arm and the tongue of the companion main bracket where it is secured by a pin 18 passing through aligned openings formed in the foot and in the arm and tongue of the main bracket. By bending the upper end of the inner arm of the U-shaped base or foot 16, a lip 19 is formed which engages over the upper edge face of the arm 5 and assists in supporting the foot between the arm and the tongue 14 and prevents the auxiliary bracket from turning about the pin 18 out of perpendicular position.

In the embodiment of the invention illustrated in Figs. 1 through 4 of the drawings, the upper portion of the metal strip from which the auxiliary bracket is formed, is bent to form a U-shaped socket 20 of proper dimensions to receive a cur-

tain pole. The curtain pole may be of wood or metal and may support overdrapes for a curtain carried by the rod 15 or this pole may carry the curtains, in which case the rod 15 will not be used. The upper end of the outer arm of the socket 20 is rolled outwardly and downwardly to impart a neat appearance thereto and also permit the curtain pole to be easily snapped into the socket where it will be firmly gripped between 10 the arms of the socket.

Instead of forming the auxiliary bracket with a U-shaped pole-receiving socket, the upper portion of the strip from which the bracket is formed may be bent forwardly to form an arm 22 and 15 then bent downwardly and upwardly to form a narrow U-shaped socket 23 of dimensions adapting it to hold a flat curtain rod formed of metal and adapted to hold overdrapes. The outer arm of the socket 23 extends upwardly above the 20 inner arm thereof and is rolled outwardly and downwardly to form a lip 24 serving to guide the curtain rod into the socket. This form of bracket is illustrated in Fig. 5 of the drawings.

In Fig. 7, there has been shown an auxiliary 25 bracket having another modified form of rod-receiving socket. Referring to this figure, it will be seen that the upper portion of the metal strip is bent forwardly, then downwardly, and then inwardly to form a socket 24. This socket 30 extends horizontally from the shank 17 and is of oblong or other rectangular outline, its upper and lower portions being formed with openings 35 to receive a pin for firmly securing a curtain rod in the socket.

When curtain supports or brackets of the improved construction are in use, they are mounted at opposite sides of a window frame, the main brackets 2 being secured against inner side faces 40 of the side portions 6 of the frame with their arms 5 extending horizontally across said side portions 6 and the auxiliary brackets extending upwardly from the arms adjacent outer side edges of the frame. A rod for carrying a main curtain is engaged with the free inner end portions 45 of the tongues and a rod for carrying overdrapes is mounted in the sockets of the auxiliary bracket. By using an auxiliary bracket of the formation shown in Figs. 1 through 4, a curtain pole of sufficient strength to support heavy over- 50 drapes may be supported, or a main curtain may be supported from this pole, in which case a rod carried by the tongues will be eliminated. Other types of rods for carrying overdrapes may be mounted in sockets of the type shown in Fig. 5 55 and in Figs. 6 and 7. Rods of small diameter may be supported by having their end portions passed through the rolled ends 21 and 24 of the auxiliary brackets. In view of the fact that the main brackets are secured to the window frame by 60 fasteners 10 passed through their end portions 8 and into the tracks 9 for the inner sash, exposed surfaces of the window frame will not be marred and the brackets may be removed without the appearance of the window frame being 65 spoiled.

Having thus described the invention, what is claimed is:

1. A support of the character described comprising a main bracket adapted to be secured to a side portion of a window frame and having an arm for extending horizontally across a side portion of the window frame and a horizontal rod supporting tongue spaced forwardly from the arm, an auxiliary bracket disposed vertically 70 and having a U-shaped base mounted between the arm and tongue of the main bracket and a fastener passing through the base and through the arm and the tongue of the main bracket to firmly hold the auxiliary bracket in place. 75
2. A support of the character described comprising a main bracket formed from a strip bent to form a shank and an arm extending horizontally therefrom for extending across a side portion of a window frame, the arm being folded 10 back in spaced relation to itself to provide an inner portion and an outer portion having a free end for engaging and supporting one end of a curtain rod, an auxiliary bracket having curtain rod engaging means and a shank depending 15 therefrom with its lower portion fitting snugly between the inner and outer portions of the arm of the main bracket, and means to hold said lower end portion of the standard in engagement with said portions of the arm of the main 20 bracket. 25
3. A support of the character described comprising a main bracket formed from a strip bent to form a shank and an arm extending laterally therefrom for extending across a side portion of a window frame, the arm being folded back in spaced relation to itself to provide a tongue having a free end for engaging and supporting one end of a curtain rod, and an auxiliary bracket formed from a strip disposed vertically and having its lower end bent to form a U-shaped base engaging the arm and tongue of the main bracket and having a lip resting upon the upper edge of the arm, and a fastener passing through 30 said base and the arm and tongue to firmly hold 35 the auxiliary bracket thereto, the upper portion of the vertical strip being bent to form a rod supporting socket. 40
4. A support of the character described comprising a main bracket, a shank and an arm 45 extending horizontally therefrom for extending across a side portion of a window frame, the arm being folded back in spaced relation to itself to provide a tongue having a free end for engaging and supporting one end of a curtain rod, and an auxiliary bracket formed from a strip disposed vertically and having its lower end bent to form a U-shaped base fitting between the arm and tongue of the main bracket, and a fastener passing through 50 said base and the arm and tongue to firmly hold the auxiliary bracket thereto, the upper portion of the vertical strip being bent to form a curtain-pole supporting member. 55
5. A support of the character described comprising a main bracket formed from a strip bent to form a shank and an arm extending laterally therefrom for extending across a side portion of a window frame, the arm being folded back in spaced relation to itself to provide a tongue 60 having a free end for engaging and supporting one end of a curtain rod, and an auxiliary bracket formed from a strip disposed vertically and having its lower end bent to form a U-shaped base fitting between the arm and tongue of 65 the main bracket and having a lip resting upon the upper edge of the arm, and a fastener passing through said base and the arm and tongue to firmly hold the auxiliary bracket thereto, the upper portion of the vertical strip being bent 70 forwardly and then downwardly and inwardly to form a rod receiving socket. 75
